TABLE AND SHELF UNIT

Harry R. Trout and Frederick M. Hill, Pittsburgh,
Pa., assignors to American Radiator & Stand-
ard Sanitary Corporation, Pittsburgh, Pa., a
corporation of Delaware

Application January 2, 1953, Serial No. 22,975

Term of patent 14 years

(Cl. D33—14)

To all whom it may concern:

Be it known that we, Harry R. Trout and
Frederick M. Hill, citizens of the United States,
residing at Pittsburgh, State of Pennsylvania,
have invented a new, original, and ornamental
Design for a Table and Shelf Unit, of which the
following is a specification, reference being had
to the accompanying drawing, forming a part
hereof.

The single figure is a perspective view of a table
and shelf unit showing our new design, the dotted

line showing of a cabinet being for illustrative
purposes only.

We claim:

The ornamental design for a table and shelf
unit, substantially as shown and described.
